EUGEN REISZ, OF BERLIN-DAHLEM, GERMANY

ELECTROSTATIC LOUD-SPEAKER

Application filed December 26, 1928, Serial No. 328,598, and in Germany December 29, 1927.

This invention relates to electrostatic loud speakers and the like, and more particularly to electrostatic loud speakers of the kind in which a soft ductile membrane, provided with a very thin conducting coating, co-operates with a rigid perforated metallic plate to form a condenser.

It is well known that loud speakers, whether electromagnetic or electrostatic, can only convert the electrical energy supplied to them into corresponding acoustic energy within definite amplitudes, and if the energy is increased beyond the limits corresponding to these amplitudes, the vibrating magnetic or electrostatic members influence the constant field in which they operate in such a manner that the sound amplitudes produced by the loud speaker are no longer proportional to the applied electrical amplitudes and distortion consequently occurs.

According to this invention the rigid conducting plate of an electrostatic loud speaker of the kind referred to is formed with holes or perforations of such shape that, even with large amplitude vibrations, the electrostatic forces upon the membrane, and therefore the movement thereof, remain proportional to the applied electrical amplitudes.

The invention is illustrated in the accompanying drawings in which

Figure 1 shows the essential portions of a loud speaker in accordance with the said invention,

Figures 2 and 3 are enlarged fragmentary views of a portion of the said loud speaker with its membrane in two different positions, while

Figure 4 indicates diagrammatically the chief positions of the membrane during its oscillations.

Referring to the drawings, *a* is a membrane, for example, of rubber, upon which is affixed a thin layer *b* of a conducting material, as, for example, carbon particles or a very thin metal foil. The membrane *a* is placed against a rigid metal plate *c* provided with holes *e* whose exterior walls *f* are curved parabolically as shown. The exact form of this curve, i. e. the parabola, determines the distribution of the electrostatic field, and the

dimensions of the said curve will clearly depend upon the stiffness of the membrane *a* (taking into account, of course, the coating *b*) and the value of the constant component of the electrostatic field, i. e. the value of the bias field. This bias field, which is due to the constant component of potential applied to the loud speaker, and the value of the rigidity of the portions *a* and *b*, determine the exact course of the line *f*.

It has been found, as a result of a large number of experiments, that for the desired result the curve *f* should be a parabola, in which stiffness of the membrane and electrostatic bias of the loud speaker are the variables. Obviously, the dielectric constant of the insulating material employed, i. e. of the membrane, will affect the dimensions of the parabola, but since the experiments referred to have all been made with one and the same insulating material as membrane, this consideration is not contained in the parabola equation.

It will be seen that when the membrane oscillates towards and away from the openings *e* in the solid metal electrode *c* of the loud speaker, a large number of small separate membranes is, in effect, produced, the said small membranes being in the un tensioned condition bounded by the line *x* (Figure 4). If, now, tension is applied, the flexible member *a* with its conducting coating *b* approaches the metal electrode and takes up the position shown by the curve *y*. Under the effect of varying applied potentials (acoustic potentials) between the electrode *c* and the coating *b*, the "limiting" curve moves to and fro, that is to say, the membrane moves into the positions shown at *x'* and *y'*. If the exterior walls of the openings *e* are of parabolic form, as indicated in Figure 4, then the electrostatic field between the electrode and coating *b* will remain the same during movements of the membrane, since the air spaces between the said plate *c* and oscillating membrane remain the same. In this way the loud speaker operates satisfactorily even when the magnitude of the potential amplitudes is very large.

I claim:

1. In an electrostatic acoustic device, a metallic plate having openings through the same, a soft ductile membrane, and a coating of a conducting material on one side of said membrane, said membrane being arranged with its uncoated side opposed to an adjacent side of said plate to produce a structure having the characteristics of a condenser, the walls of the said openings being shaped to substantially parabolic form toward that side of said plate opposed to the said membrane.
2. In an electrostatic loud speaker or the like, a rigid metallic plate having openings through the same, a soft ductile membrane and a relatively thin coating of a conducting material on one side of said membrane, said membrane being arranged with its uncoated side directly opposed to an adjacent side of said plate to produce a structure having the characteristics of a condenser, the walls of the said openings toward the ends thereof at the side of said plate opposed by said membrane being shaped to substantially parabolic form.
- 25 In testimony whereof I have signed my name to this specification.

EUGEN REISZ.
